[57] CLAIM

The ornamental design for a combined bingo bag kit and seat cushion, as shown and described.

DESCRIPTION

FIG. 1 is a front elevational view of a combined bingo bag kit and seat cushion, showing my new design;

FIG. 2 is a rear elevational view thereof;

FIG. 3 is an enlarged left side elevational view thereof, the opposite side being a mirror image except for the carrying strap;

FIG. 4 is an enlarged bottom plan view thereof;

FIG. 5 is an enlarged top plan view thereof;

FIG. 6 is a front perspective view thereof on a reduced scale; and,

FIG. 7 is a rear perspective view thereof with the rear flap in open condition, on a reduced scale.

The cross hatch shading, represents conventional fabric and is understood to extend uniformly throughout the areas represented.

The broken lines in FIGS. 1-7 represent stitching.
